ments, to The Texas Company, New York,
N. Y., a corporation of Delaware

Application December 31, 1940, Serial No. 372,453

6 Claims. (Cl. 196—49)

This invention relates to a combination thermal cracking and coking and catalytic cracking process for the production of a maximum yield of high antiknock gasoline or motor fuel.

The invention contemplates a method of processing in a unitary operation relatively light charging stocks adapted for catalytic cracking and heavier charging stocks adapted for thermal cracking. In accordance with the invention a stock suitable for catalytic cracking such as gas oil is subjected to catalytic cracking while the heavier stock such as topped or reduced crude petroleum is introduced into a fractionating zone in which vapors from the thermal cracking and coking operations are subjected to fractionation and wherein a resultant mixture of unvaporized charging stock and reflux condensate is separated from uncondensed vapors. The latter vapors are subjected to further fractionation to separate a desired gasoline or naphtha distillate from reflux condensate which is cycled to a heating zone in which the condensate is heated to a cracking temperature. The products from the catalytic cracking operation and the mixture of unvaporized charging stock and reflux condensate from the fractionating zone are combined with the heated products from the heating zone for thermal cracking in a reaction zone. The cracked products are separated into vapors and residue and the residue is passed to a coking zone wherein conversion to a coke residue occurs. In accordance with the invention a portion of the vapors sufficient to effect coking is included with the residue which is passed to the coking zone. By including such portion of vapors with the residue it is possible to effect autogenous coking of the residue under high charging and recycling rates without producing priming in the coking drum. Vapors from the coking operation are subjected to fractionation together with the vapors from the cracking operation. In a preferred embodiment of the invention the vapors from the coking drum are subjected to a primary condensation or dephlegmation to form a heavy tarry condensate and the uncondensed vapors are passed to the fractionating zone receiving the vapors from the cracking operation.

The invention contemplates a process wherein charging stock such as crude petroleum is fractionated to form a heavy fraction adapted for thermal cracking and a lighter fraction adapted for catalytic cracking. The heavy fraction is subjected to cracking in a thermal cracking operation by being combined with the hot products

from a recycling heating or cracking coil. The heavy fraction is advantageously charged to the dephlegmator receiving vapors from the thermal cracking operation and the resultant mixture of reflux condensate and unvaporized constituents of the heavy fraction is brought into contact with the heated products from a recycling thermal cracking zone and the mixture subjected to cracking in a reaction zone. The lighter fraction from the crude fractionation is directed to a catalytic cracking zone and products from the catalytic cracking zone are admixed with products from the thermal recycling heating or cracking zone and with the mixture of heavy reflux condensate and unvaporized constituents of the heavy fraction from the crude. The commingled constituents are subjected to cracking and the cracked products separated into vapors and residue, the residue converted to coke, the evolved vapors from both the cracking and coking operations dephlegmated with the heavy fraction from the crude and the vapors further fractionated to form a clean recycle stock for passage to the thermal heating coil.

The thermal re-cracking of the catalytically cracked products conditions such products or renders them suitable for further catalytic cracking and in accordance with the invention the products resulting from the thermal cracking, including the re-cracking of the catalytically cracked products, are fractionated to separate out heavy constituents adapted for being combined with the products from the recycling condensate heating coil and lighter or intermediate constituents adapted for recycling to the heating or cracking coil and adapted also for cracking in the catalytic cracking zone.

In a modification of the invention products from the catalytic cracking operation are delivered to the fractionating zone of the thermal cracking operation so that the catalytically cracked products may be fractionated together with the thermally cracked products and heavier constituents of the catalytic cracking passed to the thermal cracking zone while the gasoline or motor fuel constituents are collected together with the thermally cracked gasoline or motor fuel constituents.

For the purpose of more fully disclosing the invention reference is now had to the accompanying drawing which is a flow diagram indicating an apparatus adapted for the practice of the invention.

Referring to the drawing the charging stock

such as crude petroleum is drawn from a suitable source by a pump 10 which directs the charge through a heating coil 11 which is suitably heated by heat exchange with hot cracked products of the system or otherwise to raise the oil to a desired distilling temperature. The heated oil is discharged into a tower 12 for separation into vapors and residue and fractionation of the vapors. A condensate fraction suitable for catalytic cracking is collected on a tray 13 and lighter vapors pass overhead to a condenser coil 14, light distillate such as naphtha or gasoline being collected in a receiving drum 15.

Condensate from tray 13 is drawn through a line 16 and directed by a pump 17 through a line 18 to a heating coil 19 disposed in a furnace 20 adapted for heating the oil to a temperature suitable for catalytic cracking. The heated oil passes from the heating coil to a catalyst case 21 containing a bed of catalytic material.

The catalyst consists advantageously of a synthetic silica-alumina type of catalyst. Various acid-treated and metal-substituted clays such as the Super-Filtrols and acid-treated and metal-substituted natural or artificial zeolites, such as the artificial zeolite known as Doucile may be employed. Various metals such as uranium, molybdenum, manganese, lead, zinc, zirconium, nickel and the like, may be substituted in the clays or zeolites. Likewise, the combination of certain acid-treated active clays of the character of Filtral, together with added proportions of alumina or silica or both may be employed. Alumina alone may be used under certain conditions. The synthetic alumina catalysts can be improved by the addition of other constituents such as zirconium oxide or molybdenum oxide.

The thermal cracking portion of the system includes a heating coil 22 mounted in a suitable furnace 23, a reaction and separating chamber 24, a coking drum 25, a primary fractionating tower 26 and a secondary fractionating tower 27. Residue from the crude stripping tower 12 is drawn by pump 28 and directed through a line 29 to the fractionating tower 26 wherein the vapors are dephlegmated with the crude residuum and a resultant mixture of heavy reflux condensate and unvaporized residue is collected on a tray 30. This mixture is withdrawn by a pump 31 and passed through a line 32 to a transfer line 33 extending from the heating coil 22 to the reaction chamber 24, so that the mixture of reflux condensate and unvaporized crude residuum is combined with the hot products from the heating coil 22 for cracking in the reaction chamber 24. Separation of vapors from residue takes place in the reaction chamber and residue is withdrawn through a line 34 having a pressure reducing valve 35 and extending to the coking drum 25. Separated vapors pass from the reaction chamber through a vapor line 36 having a pressure reducing valve 37 and extending to the tower 26, the vapor line preferably entering the tower above the trapout tray 30. Vapors from the coking drum 25 pass through a line 38 to a lower section 39 of the tower 26 beneath the tray 30 in which section the vapors from the coking operation are subjected to a primary condensation or dephlegmation to form a heavy tarry distillate which may be withdrawn through a line 40. A portion of the reflux condensate from tower 27 may be cooled and refluxed in the dephlegmator 39 and a portion of the tarry distillate withdrawn through line 40 may be cycled back to the chamber 39 to provide liquid flow

therein to prevent deposition of coke. The uncondensed vapors pass from tower 26 through a line 41 to the fractionating tower 27 wherein the vapors are further fractionated. The tower is provided with appropriate cooling or refluxing means. The overhead vapors pass to a condenser 42 and the distillate is collected in a receiving drum or gas separator 43. Reflux condensate from the tower 27 is withdrawn through a line 44 and directed by a pump 45 to the heating coil 22.

The products from the catalyst case 21 are passed through a line 46 to the transfer line 33 to be commingled therein with the heated products from the coil 22 as well as with the mixture of heavy reflux condensate and unvaporized residue being received from the tray 30 of tower 26 and the combined streams are subjected to thermal cracking in the reaction chamber 24. When passing the products from the catalytic cracking operation to the reaction chamber 24 the pressure in the catalyst case must be sufficient to insure the delivery of the products to the reaction chamber. It is generally desirable to maintain pressures approximating 200 lbs. or even higher in the thermal reaction chamber 24 and consequently the pressure in the catalyst case should be somewhat higher, for example, 210 lbs. In such operation it is sometimes desirable to carry on cracking in the heating coil 22 at a pressure somewhat higher than is maintained in the reaction chamber 24 and, for this purpose a pressure reducing valve 56 may be inserted in the transfer line 33. Thus, for example, the heating coil outlet may be held at a pressure of 400 lbs. and the pressure dropped to about 200 lbs. in the reaction chamber 24 while a pressure of 205-210 lbs. is maintained in the catalyst case 21.

In a modification of the invention the products from the catalyst case are delivered to the fractionating zone of the thermal cracking operation and for this purpose the line 46 may be provided with a branch line 47 extending to the tower 26 the line preferably entering the tower above the trapout tray 30. In this modified operation lower pressures such as 50-100 lbs. may well be maintained in the catalyst case. The pressure in the coking drum is normally of the order of 50-100 lbs. and ordinarily it is not necessary to carry any higher pressure in the catalyst case other than that sufficient to insure the delivery of the cracked products to the fractionator 26.

The catalytic cracking operation may advantageously be restricted to a single pass operation for cracking the straight run gas oil stock. It is sometimes expedient however to recycle condensate, particularly condensate derived from a thermal cracking operation, back to the catalytic cracking zone. For this purpose line 44 may be equipped with a branch line 48 extending to a pump 49 by which a portion of the reflux condensate from the tower 27 may be directed through a line 50 to the coil 19.

In practicing the invention a straight run stock of the nature of gas oil or kerosene is passed through the heating coil 19 wherein it is heated sufficiently to maintain cracking temperatures of the order of 850° F.-1050° F. and preferably temperatures of about 910° F.-1000° F. in the catalyst case. When using the catalysts disclosed herein relatively low superatmospheric pressures under 100 lbs. and even ranging down to approximately atmospheric are quite satisfactory, but when directing the catalytically cracked products to the reaction chamber 24 it is necessary to accommodate the catalytic cracking zone pres-

sure to that employed in the thermal reaction chamber where pressures upwards of 200 lbs. are generally desirable, although pressures approximately as low as 100 lbs. may at times be employed. The reflux condensate cycled from the tower 27 to the heating coil 22 is subjected to temperatures of the order of 950° F. to 1050° F. under superatmospheric pressures such as 400-800 lbs. The topped or reduced crude from the crude stripping tower is directed to the fractionator 26 and the resultant mixture of reflux condensate and crude residuum at a temperature of the order of 750° F. to about 800° F. is withdrawn from the tray 30 and combined with the heated products from coil 22 and with the products from the catalytic cracking chamber 21 for reaction in the thermal reaction chamber 24 wherein the commingled products are subjected to thermal cracking at cracking temperatures of about 900° F.-930° F. are maintained under a superatmospheric pressure preferably as high as about 200 lbs. Liquid is prevented from accumulating in the reaction chamber, the residue together with a sufficient quantity of vapors to effect coking being rapidly withdrawn from the bottom of the chamber and delivered to the coking drum wherein autogenous coking takes place while the separated vapors pass to the fractionator 26. Coking is carried on in the chamber 25 under pressures of about 50-100 lbs. or lower and at temperatures of about 825° F.-850° F. The evolved vapors are dephlegmated in chamber 39 to form a heavy tarry condensate which constitutes a distillate fuel oil product. If desired this product may be flash distilled to produce a final fuel oil product of desired gravity or flash test. The pressure in the fractionator 26 will normally approximate the pressure in the coking drum 25.

The operation in which the products from the catalytic cracking case 21 are directed to line 41 to the fractionator 26 has a particular advantage in that it facilitates the maintenance of relatively low pressures in the catalyst case which low pressures, as has been stated, are quite satisfactory. In this operation the residual products of the catalytic cracking together with the residual products of the topped or reduced crude charging stock which collect on the tray 30 are combined with the heated cycle condensate for cracking in the reaction chamber 24, while lighter constituents of the catalytic cracking are distilled over into the tower 27.

In some cases, particularly when the crude residual stock charged to the tower 26 contains relatively large proportions of gas oil constituents, it is advantageous to pass a portion of the reflux condensate drawn from the tower 27 to the catalytic cracking zone.

The heavy, tarry condensate withdrawn from separator 39 through line 40 makes an excellent fuel oil but in case such a product is not desired, the tarry condensate may be directed to the reaction chamber 24, or preferably to the coking drum 25.

While we have described a particular embodiment of our invention for purposes of illustration, it should be understood that various modifications and adaptations thereof which will be obvious to one skilled in the art, may be made within the spirit of the invention as set forth in the appended claims.

We claim:

1. In the conversion of hydrocarbon oils the process that comprises distilling crude petroleum to separate a residue from a lighter fraction, sub-

jecting said lighter fraction to catalytic cracking, introducing said residue into a fractionating zone wherein fractionation takes place to separate a resultant mixture of unvaporized residue and heavy reflux condensate from uncondensed vapors, subjecting the uncondensed vapors to further fractionation to separate a distillate product from reflux condensate, directing said reflux condensate to a heating coil wherein the oil is heated to a cracking temperature, passing the resultant heated products to a reaction zone, directing the products from the catalytic cracking to said reaction zone, directing said mixture of unvaporized residue and heavy reflux condensate to said reaction zone, subjecting the resultant mixture in the reaction zone to cracking conditions of temperature and pressure to produce further cracking and effecting a separation of residual constituents from vapors, passing resultant separated vapors to the aforesaid fractionating zone, subjecting said residual constituents to coking, and passing evolved vapors from the coking operation to said fractionating zone.

2. In the conversion of hydrocarbon oils the process that comprises distilling crude petroleum to separate a residue from a lighter fraction, subjecting said lighter fraction to catalytic cracking, introducing said residue into a fractionating zone wherein fractionation takes place to separate a resultant mixture of unvaporized residue and heavy reflux condensate from uncondensed vapors, subjecting the uncondensed vapors to further fractionation to separate a distillate product from reflux condensate, directing said reflux condensate to a heating coil wherein the oil is heated to a cracking temperature, passing the resultant heated products to a reaction zone, directing the products from the catalytic cracking to said reaction zone, directing said mixture of unvaporized residue and heavy reflux condensate to said reaction zone, subjecting the resultant mixture in the reaction zone to cracking conditions of temperature and pressure to produce further cracking and effecting a separation of residual constituents from vapors, passing resultant separated vapors to the aforesaid fractionating zone, subjecting said residual constituents to coking, subjecting the evolved vapors from the coking operation to a primary dephlegmation to separate a tarry distillate, withdrawing said tarry distillate as a fuel oil product of the process and passing the dephlegmated vapors to said fractionating zone.

3. In the conversion of hydrocarbon oils the process that comprises distilling crude petroleum to separate a residue from a lighter fraction, subjecting said lighter fraction to catalytic cracking, introducing said residue into a fractionating zone wherein fractionation takes place to separate a resultant mixture of unvaporized residue and heavy reflux condensate from uncondensed vapors, subjecting the uncondensed vapors to further fractionation to separate a distillate product from reflux condensate, directing said reflux condensate to a heating coil wherein the oil is heated to a cracking temperature, combining the resultant heated products with the products from the catalytic cracking operation and with said mixture of unvaporized residue and heavy reflux condensate for cracking in a reaction chamber wherein separation of vapors from liquid residue takes place, maintaining cracking conditions of temperature and pressure in said reaction chamber, passing resultant separated vapors

to the aforesaid fractionating zone, withdrawing liquid residue together with a portion of the vapors from the reaction chamber and delivering the mixture to a coking zone wherein coking takes place, the proportion of vapors so withdrawn being sufficient to effect autogenous coking of the mixture and passing evolved vapors from the coking operation to said fractionating zone.

4. In the conversion of hydrocarbon oils the process that comprises distilling crude petroleum to separate a residue from a lighter fraction, subjecting said lighter fraction to catalytic cracking in a catalytic cracking zone, introducing said residue into a fractionating zone wherein fractionation takes place to separate a resultant mixture of unvaporized residue and heavy reflux condensate from uncondensed vapors, passing uncondensed vapors to a second fractionating zone wherein the vapors are fractionated to separate a distillate product from reflux condensate, directing one portion of the reflux condensate from the second fractionating zone to a heating coil wherein the oil is heated to a cracking temperature, passing the resultant heated products to a reaction zone, directing the products from the catalytic cracking to said reaction zone, directing said mixture of unvaporized residue and heavy reflux condensate to said reaction zone, subjecting the resultant mixture in the reaction zone to cracking conditions of temperature and pressure to produce further cracking and effecting a separation of residual constituents from vapors, passing resultant separated vapors to the first-mentioned fractionating zone, subjecting said residual constituents to coking, passing evolved vapors from the coking operation to said fractionating zone and directing another portion of the reflux condensate from the second fractionating zone to the aforesaid catalytic cracking zone.

5. In the conversion of hydrocarbon oils the method of treating a residual stock and a condensate stock that comprises subjecting the condensate stock to catalytic cracking, introducing the residual stock into a fractionating zone wherein fractionation takes place to separate a resultant mixture of unvaporized residue and heavy reflux condensate from uncondensed vapors, subjecting the uncondensed vapors to further fractionation to separate a distillate product from

reflux condensate, directing said reflux condensate to a heating coil wherein the oil is heated to a cracking temperature, passing the resultant heated products to a reaction zone, directing the products from the catalytic cracking to said reaction zone, directing said mixture of unvaporized residue and heavy reflux condensate to said reaction zone, subjecting the resultant mixture in the reaction zone to cracking conditions of temperature and pressure to produce further cracking and effecting a separation of residual constituents from vapors, passing resultant separated vapors to the aforesaid fractionating zone, subjecting said residual constituents to coking and passing evolved vapors from the coking operation to said fractionating zone.

6. In the conversion of hydrocarbon oils the method of treating a residual stock and a condensate stock that comprises subjecting the condensate stock to catalytic cracking, introducing the residual stock into a fractionating zone wherein fractionation takes place to separate a resultant mixture of unvaporized residue and heavy reflux condensate from uncondensed vapors, subjecting the uncondensed vapors to further fractionation to separate a distillate product from reflux condensate, directing said reflux condensate to a heating coil wherein the oil is heated to a cracking temperature, passing the resultant heated products to a reaction zone, directing said mixture of unvaporized residue and heavy reflux condensate to said reaction zone, subjecting the resultant mixture in the reaction zone to cracking conditions of temperature and pressure to produce further cracking and effecting a separation of residual constituents from vapors, passing resultant separated vapors to the aforesaid fractionating zone, subjecting said residual constituents to coking, passing evolved vapors from the coking operation to said fractionating zone and directing the products from the catalytic cracking operation to the aforesaid fractionating zone from fractionation therein so that the heavier constituents of the catalytic cracked products are combined with said mixture of unvaporized residue and heavy reflux condensate being passed to said reaction zone.
